UNITED STATES PATENT OFFICE

PHILIP G. LLOYD, OF BALTIMORE, MARYLAND, ASSIGNOR TO CARR-LOWREY GLASS COMPANY, OF BALTIMORE, MARYLAND

SPRINKLER BOTTLE

Application filed April 18, 1930. Serial No. 445,435.

This invention relates to a sprinkler bottle, one of the objects being to provide a bottle the neck portion of which is so shaped and so proportioned that the contents of the bottle can not flow freely but, instead, it becomes necessary to shake the bottle in order to expel its contents.

Heretofore, in order to produce a sprinkler it has been necessary to provide a separate attachment to be placed on the neck of the bottle. The present invention aims to eliminate a separate sprinkling attachment.

A still further object is to provide a bottle of this character the neck portion or finish of which can be produced by ordinary methods of manufacture.

With the foregoing and other objects in view which will appear as the description proceeds, the invention resides in the combination and arrangement of parts in the details of construction hereinafter described and claimed, it being understood that changes in the precise embodiment of the invention herein disclosed may be made within the scope 25 of what is claimed without departing from the spirit of the invention.

In the accompanying drawings the preferred form of the invention has been shown.

In said drawings

Figure 1 is a side elevation of a bottle provided with the finish or neck portion constituting the present invention.

Figure 2 is a view partly in front elevation and partly in section of a bottle provided with the present improvement.

Figure 3 is a view similar to Figure 2 showing the bottle partly filled and positioned to allow its contents to be shaken therefrom.

Referring to the figures by characters of reference 1 designates a bottle or other container of glass which can be of any shape desired. This container has a neck 2 formed, at a point between its ends, with an interior annular shoulder 3 disposed in a plane perpendicular to the central longitudinal axis of the neck and concentric therewith. The outer portion of the neck has an opening 4 of less diameter than the opening in the inner or base portion of the neck. That portion of the neck surrounding the opening 4 is of re-

duced diameter and has moulded on it a continuous screw thread indicated at 5 whereby a closure in the form of a screw cap can be connected to the neck. Below this reduced portion is an annular enlargement 6 providing spaced annular shoulders 7 and 8. The shoulder 7 constitutes an abutment for a screw cap when placed in engagement with the thread 5. The lower or skirt portion of the cap can be extended around the enlargement 6 which forms a collar adapted to be engaged snugly by the skirt of the cap as will be obvious.

It has been found in practice that when a bottle is constructed as herein described with the neck or finish formed with the interior annular shoulder 3 and with the opening 4 of less diameter than the inner portion of the opening in the neck, it becomes impossible for liquid to flow freely from the bottle when in an inclined or an inverted position. It is only by shaking the bottle that the liquid can be expelled in desired quantities. Under these conditions the liquid will not be discharged in small drops, as would be the case should the neck opening be tapered toward the outlet, but will be delivered in short streams due, apparently, to the fact that all but the central portion of the body of liquid is held back by the flat shoulder 3 during the expelling action and there is no instantaneous choke such as would occur in a tapered passage. Instead the choking action takes place after a short stream of unrestrained liquid has been delivered, this choking action being due to the tendency of the restrained liquid back of shoulder 3 to flow toward the center of the neck passage after the stream of unrestrained liquid has been delivered.

When the bottle is not in use a cap can be placed on the neck finish as has already been explained, thereby sealing the contents.

What is claimed is:

1. A device of the class described having a neck portion with an opening extending therethrough, the outer portion of the opening being of less diameter than the inner portion, there being an abrupt interior annular shoulder between said portions of the

opening constituting liquid restraining means.

5 2. A bottle or the like having a sprinkler finish including a neck portion provided with an opening, the outer portion of the opening being of less diameter than the inner portion, and said portions co-operating to provide a flat interior annular shoulder perpendicular to the axis of the opening.

10 3. A bottle or the like having a sprinkler finish including a neck portion provided with an opening, the outer portion of the opening being of less diameter than the inner portion, and said portions co-operating to provide a flat interior annular shoulder perpendicular to the axis of the opening, a reinforcing collar extending around that portion of the neck forming the interior shoulder, said collar providing an annular shoulder constituting an abutment for a cap when placed upon the neck portion and around the collar.

15 In testimony that I claim the foregoing as my own, I have hereto affixed my signature.

20 PHILIP G. LLOYD.
